(57) **CLAIM**

The ornamental design for a carpet type body fat meter, as shown and described.

DESCRIPTION

FIG. 1 is a perspective view of a carpet type body fat meter showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is the other perspective view thereof; and,

FIG. 9 is a perspective view showing the carpet type body fat meter in use.

The broken lines shown represent unclaimed subject matter and form no part of the claimed design.
